LEG EXERCISER

Earl E. Longfellow, Warsaw, Ind., assignor to Harry Herschel Leiter, Warsaw, Ind.

Application January 13, 1949, Serial No. 213

Term of patent 14 years

(Cl. D34—5)

To all whom it may concern:

Be it known that I, Earl E. Longfellow, a citizen of the United States, residing at Warsaw, in the county of Kosciusko and State of Indiana, have invented a new, original, and ornamental Design for a Leg Exerciser of which the following is a specification, reference being had to the accompanying drawing, forming a part hereof.

The single figure is a perspective view of a leg exerciser, showing my new design.

I claim:

The ornamental design for a leg exerciser, as shown.

EARL E. LONGFELLOW.
